(57) **CLAIM**

The ornamental design for a cracking die for a nutcracking die assembly, as shown and described.

(**) Term: **14 Years**

DESCRIPTION

(21) Appl. No.: **29/171,215**

FIG. 1 is a perspective view of a cracking die for a nutcracking die assembly which embodies the present invention;

(22) Filed: **Nov. 19, 2002**

FIG. 2 is a side elevation view of the cracking die shown in FIG. 1;

(51) LOC (7) Cl. **15-09**

FIG. 3 is a front elevation view of the cracking die shown in FIG. 1;

(52) U.S. Cl. **D15/123**

FIG. 4 is a rear elevation view of the cracking die shown in FIG. 1; and,

(58) Field of Search D15/122, 123;
30/120.1-120.5; 99/568, 571-576, 577-579,
580-583, 600; 198/622; 426/481, 482

FIG. 5 is a sectional view taken along the line 5—5 in FIG. 3.
